UNITED STATES PATENT OFFICE

1,957,194

EXTENSION FOR TABLE LEGS

Olaf J. Arness, Chicago, Ill.

Application September 16, 1932, Serial No. 633,472

1 Claim. (Cl. 45—48)

The present invention has to do with a device for the elongation of a table leg and is particularly suited for use upon a conventional bridge table or the like. The utility of the device in no way, however, is limited to bridge tables, but on the contrary, its use for other articles of furniture is legion.

Among the objects of the invention are the following:

10 A new and improved means for lengthening a table leg or similar device.

A novel table leg extension device.

A unique blank for the production of a table leg extension or the like.

15 An improved article of manufacture for use with tables and the like and attachable thereto for the purpose of providing an extension to the legs thereof.

These, and such others as may hereinafter appear are obtained by the novel construction, unique combination, and improved arrangement of several elements which constitute the single form of the invention illustrated in the accompanying drawing, hereby made a part of this 20 specification, and in which:

Figure 1 is a perspective view of a table leg with one of the devices embodying the invention attached thereto;

Figure 2 is a vertical longitudinal section taken 25 on the line 2—2 of Figure 1 and showing the fabricated device; and

Figure 3 is a plan view of a blank from which the device shown in Figure 2 is adapted to be folded.

30 Like reference characters are used to designate similar parts in the drawing and in the description of the invention which follows.

One leg only of a table is shown. Each leg of such a table such as is illustrated will be equipped 35 with a device similar to that shown in the several figures of the drawing.

In said Figure 1, the table leg is designated 10. The device attached thereto comprises a bottom 40 face of portion 11, and elongated extensions 12 and 13 integral with the part 11, said extensions extending upwardly of the table leg 10. On the edges of the bottom plate 11 where side members 12 and 13 do not join said plate are short triangular upwardly pointed extensions 14 and 15.

45 The extensions or side members 12 and 13 each have flanges which are turned inwardly about the table leg 10, the flanges being designated 16, 17, 18 and 19. At the end of said flanges adjacent the bottom portion 10, a part of the material is 50 removed to prevent overlapping the material of

the shorter extensions 14 and 15, the said shorter extensions and the flanges thus being closely associated, but spaced a predetermined distance apart.

The edges of the flanges 16, 17, 18 and 19, which are adjacent, are not parallel but the top of said flanges are tapered to permit of a wide range of adjustments in fitting the device about the table leg.

In said side members 12 and 13 are opposed 65 apertures. One pair of such apertures 20 is adapted to receive a tightening screw 21 and its socket 22. Through each of the other pair of apertures 23 a screw or tack may be inserted for penetration into the leg 10 when a permanent 70 attachment of the device to the table leg 10 is desired. In said members 12 and 13, there also may be formed teeth 25, which teeth come into contact with the material of a table leg 10 and bite thereto upon tightening of screw 21 in 75 socket 22 to prevent accidental displacement of the device longitudinally of table leg 10.

In the foregoing description, the manner in which the material of the blank shown in Figure 3 is folded is set forth. When such blank is 80 folded to provide a device shown in Figures 2 and 3, it is moved longitudinally of the table leg 10. Generally, the space between the sides 12 and 13 is such that at least slight frictional engagement with the table leg is had. Close frictional engagement is also had between the material of the table leg and flanges 16, 17, 18 and 19, so that the device is held against angular displacement on the table leg. When any desired adjustment is obtained, the adjusting screw 85 21 is tightened in socket 22 and the sides 12 and 13 are thus made to bear more tightly upon the table leg 10, accidental displacement of the device longitudinally of the leg then being positively prevented. Such screw also provides a 90 stop limiting the extension of a table leg into the sleeve formed by the blank herein described.

As stated previously, a screw or tack may be inserted in the aperture 23 to make the attachment permanent after any adjustment is made 100 in respect thereto.

When teeth 25 are employed, the tightening of the adjusting screw causes the pointed ends thereof to bite into the leg as previously stated, thus giving the connection between the leg and 105 device great security without the addition of a tack through aperture 23.

The teeth 25 and the apertures 23 for the insertion of tacks or screws into the leg of the table may be omitted if desired.

The blank may be slightly modified to fit a round table leg in which event the cross section of the extension will be round or elliptical.

What is claimed as new and desired to be secured by Letters Patent of the United States is:

A table leg extension member of an integral sheet of material and comprising a central floor-engaging section having a configuration coinciding generally with the cross section of the end 10 of a table leg on which used, and depending similar opposed elongated sections substantially nor-

mal to said floor-engaging section and gripping opposite sides of such table leg, each section extending less than half way thereabout, said central floor-engaging section also having short extensions normal to said elongated extension sections and projecting upwardly between said elongated extension sections without contact therewith, the elongated extension sections being spaced apart along their contiguous edges their entire length.
